BRIQUETTE COOLING CONVEYER

Gustav Komarek, Chicago, Ill., assignor to Komarek-Greaves and Company, Chicago, Ill., a corporation of Illinois

Application April 19, 1937, Serial No. 137,872

5 Claims. (Cl. 198—201)

The present invention relates to cooling and conveying means and is particularly useful in association with plastic forming machinery, e. g. briquette presses for continuously receiving and cooling while transferring the hot fuel briquettes as formed to a suitable discharge point.

Previous apparatus of this character has been open to the objection that the briquettes are subjected to undue agitation, whence, because of their somewhat fragile initial condition, there results a rubbing of one against the other to the extent that in some cases the briquettes are disintegrated or their preformed surface contours are rendered so irregular as to interfere with the salability of the product.

With these considerations in mind, I have developed a continuous type of conveyer for receiving the hot briquettes from the press and capable of conveying them with complete freedom from pulsations. Furthermore, the conveyer is so constructed as to afford optimum cooling conditions for the briquettes. In this manner, briquettes are continuously cooled while travelling under conditions which will prevent any substantial rubbing contact, with the result that the briquettes delivered to the discharge point are firm, have their desired preformed shape and are devoid of surface irregularities.

The construction is simple and easily adaptable with briquette presses now in use. Also, the conveyer being of the continuous type may be controlled as to speed and is so constructed that the cooling action is substantially uniform.

Various modifications in the construction may, of course, be resorted to and I have illustrated in the attached drawings and described in the following specification one preferred embodiment of the invention.

Referring to the drawings:

Figure 1 is a side elevation of the cooling conveyer, but partly broken away and in section.

Figure 2 is a top elevation of the cooling conveyer.

Figure 3 is a section on the line 3—3 of Figure 1, and

Figure 4 is a perspective view showing certain of the parts in disconnected relation.

Referring to Figure 1, the continuous conveyer is mounted upon suitable supports 10, one at each end of the conveyer, and in which are carried sprockets 11 for causing the conveyer to be continuously moved. One of the sprockets is actuated by any suitable prime mover rotating its shaft 11'.

The conveyer includes a number of sections

which are united together in the manner now to be described. Referring to Figures 3 and 4, each section has two upstanding opposed plates 12 which are identical in construction, and the plates 12 on each side of the conveyer are disposed in longitudinal alignment. Each plate has a substantially smooth inner side surface 13 and adjacent its base is thickened outwardly as shown at 14. At one end, the thickened portion is cut away to provide a curved recess 15 comprehending the transverse area of the thickened portion and extending outwardly of the recess is the offset integral boss 16 provided with an opening 17. The opposite end of each plate at the thickened base portion thereof is provided with a longitudinal projecting boss 18 having a curved contour conforming to the contour of the recess 15 and provided with an opening 19 extending therethrough. The transverse area of the boss 18 is substantially equal to that of the recess 15 in which it is received so that when the ends or edges of succeeding plates are lined up to form the respective sides of the conveyer, the openings 17 and 19 will be in register, the plane end edges 20 of the plates will be in substantially 25 abutting relation as shown in Figure 1 and the faces 13 will form a continuous side wall on each side of the conveyer.

The bottom of the conveyer includes a plurality of spaced grid rods 21 fitting in recesses or sockets 22 in the opposed plates 12 and spaced tie rods 23 whose reduced ends 24 extend through openings 25 in the plates. The rods 21 are of a length so that their ends abut the closed ends or bottoms of the recesses 22, and they are held in such positions by the tie rods 23, whereby a rigid structure is assured. The plates abut against the shoulders 26 on the tie rods 23 and are maintained in position by means of the nuts 27 engaging the threaded portions 28 on the reduced ends 24 of the tie rods. It is to be noted that the rods 21, 23 are maintained spaced apart a distance sufficient to prevent briquettes, for example, from passing therethrough, and such spacing also affords a maximum opportunity for 45 the circulation of air to promote rapid and complete cooling of the briquettes.

The ends of the respective plates or sections are hingedly connected together by means of shafts 29 extending through the registering openings 17, 19, which shafts at each end carry suitable rollers 30 held in position by cotter pins or any other suitable means 31. The rollers supporting the conveyer sections are moved by the prime mover actuated sprocket member over a 55

suitable track 32 while the conveyer is moving in its upper horizontal position and are supported upon a track 33 when the conveyer is moving in its lower horizontal position. At the ends of the conveyer, of course, the sections are engaged by the sprocket members 11.

The conveyer construction just described is free of any pulsating motion such as would agitate or cause the briquettes fed thereto from 10 a press to have a rubbing contact that might either disintegrate the briquettes or deform them. Moreover, the construction is such as to afford an optimum cooling of the briquettes so that their resistance to deformation progresses as 15 they move from the press to the discharge point. This is important in that by controlling the speed of the rotation of the sprockets and hence the travel of the conveyer, various briquette compositions can be cooled and conveyed and presented 20 at the discharge end in such condition that subsequent handling will not injure the product.

It is to be understood that the conveyer may be of any desired length and width. In some cases, in order to strengthen and rigidify the 25 slatted bottom defined by the spaced shafts 29, tie rods 28 and rods 21, I provide straps 34. As shown in Figures 1 and 2 these straps consist of upper and lower members 35, 36 having complementary semi-circular recesses 37 therein to 30 grip the respective spaced members forming the bottom, and the two sections 35—36 are bolted together as shown at 38. In the case of a narrow conveyer, one set of straps will be employed disposed substantially in central alignment, 35 whereas when the conveyer is relatively wide, the straps will be disposed in staggered relation as shown in Figure 2.

It will be noted, and as heretofore explained, that the conveyer has the adjacent end edges 40 20 of aligned plates 12 on each side of the conveyer in abutting relation as shown in Figures 1, 2 and 3, and that in the horizontal movement of the conveyer, the rollers being supported upon a continuous track 32, the conveyer sections are 45 devoid of any irregular motion such as would shuffle the briquettes about and cause them to have a rubbing contact. In this connection, the straps 34 serve to rigidify and stiffen the bottom, as well as the side walls in their abutting relation, 50 so that the conveyer is further prevented from any irregular motion.

I claim:

1. A continuous sectional cooling conveyer for briquettes including a series of longitudinally disposed guard plates constituting the sides of the 55 conveyer, each plate having a smooth inner surface and provided at its inner side with a longitudinally extending offset portion, said offset portion being provided intermediate its ends with inwardly disposed spaced sockets, one end of the 60 offset portion terminating in a transversely disposed boss and the other end provided with a laterally offset boss arranged to overlap the boss on the adjacent plate when the parts of the conveyer are set up, the overlapped bosses having 65 registering openings, grid rods extending transversely of the conveyer and having their inner ends mounted in aligned sockets in each opposed pair of plates, and shafts extending through the 70 openings in the aligned bosses for connecting the adjacent ends of the plates together, said shafts having rollers thereon for supporting the conveyer, said rods and shafts constituting a slatted bottom for the conveyer and being correctly spaced to support the briquettes so as to prevent 75 the latter from falling through the bottom, said rods and shafts also being disposed to provide a maximum amount of open spaces in the bottom effectively to cool the briquettes carried by the conveyer.

2. A continuous sectional cooling conveyer for briquettes including a series of longitudinally disposed guard plates constituting the sides of the conveyer, each plate having a smooth inner surface and provided at its inner side with a longitudinally extending enlarged offset portion, said offset portion being provided intermediate its ends with inwardly disposed spaced sockets and through openings, one of the offset portions terminating in a transversely disposed boss and the 15 other end provided with a laterally offset boss arranged to overlap the boss on the adjacent plate when the parts of the conveyer are set up, the overlapped bosses having registering openings, grid rods extending transversely of the conveyer 20 and having their ends mounted in aligned sockets in each opposed pair of plates, tie rods extending transversely through aligned openings in each opposed pair of plates, means for rigidly securing the tie rods to the plates, and shafts extending through the openings in the aligned bosses for connecting the adjacent ends of the plates together, said shafts having rollers thereon for supporting the conveyer, said rods and shafts constituting a slatted bottom for the conveyer 25 and being correctly spaced to support the briquettes so as to prevent the latter from falling through the bottom and also being disposed to provide a maximum amount of open spaces in the bottom effectively to cool the briquettes carried 30 on the conveyer.

3. A continuous sectional cooling conveyer for briquettes including a series of longitudinally disposed guard plates constituting the sides of the conveyer, each plate having a smooth inner surface and provided at its inner side with a longitudinally extending offset portion, said offset portion being provided intermediate its ends with inwardly disposed spaced sockets, one end of the offset portion terminating in a transversely disposed boss and the other end provided with a laterally offset boss arranged to overlap the boss on the adjacent plate when the parts of the conveyer are set up, the overlapped bosses having 40 registering openings, grid rods extending transversely of the conveyer and having their inner ends mounted in aligned sockets in each opposed pair of plates, shafts extending through the openings in the aligned bosses for connecting the adjacent ends of the plates together, said shafts having rollers thereon for supporting the conveyer, said rods and shafts constituting a slatted bottom for the conveyer and being correctly 45 spaced to support the briquettes so as to prevent the latter from falling through the bottom, said rods and shafts also being disposed to provide a maximum amount of open spaces in the bottom effectively to cool the briquettes carried by the conveyer, spaced sprocket wheels engaging the conveyer, and driving means connected to one 50 of the sprocket wheels for moving the conveyer, said rods and shafts being disposed in substantially longitudinal alignment so that the conveyer passes over the sprocket wheels without increasing the width of the openings between 55 the rods and thus precludes the briquettes on the conveyer from falling therethrough.

4. A continuous sectional cooling conveyer for briquettes including a series of longitudinally disposed guard plates constituting the sides of the 60

conveyer, each plate having a smooth inner surface and provided at its inner side with a longitudinally extending enlarged offset portion, said offset portion being provided intermediate its ends with inwardly disposed spaced sockets and through openings, one of the offset portions terminating in a transversely disposed boss and the other end provided with a laterally offset boss arranged to overlap the boss on the adjacent plate 5 when the parts of the conveyer are set up, the overlapped bosses having registering openings, grid rods extending transversely of the conveyer and having their ends loosely mounted in aligned sockets in each opposed pair of plates, tie rods 10 extending transversely through the aligned openings in each opposed pair of plates, means for rigidly securing the tie rods to the plates, shafts extending through the openings in the aligned bosses and having rollers thereon for supporting 15 the conveyer, spaced sprocket wheels engaging the conveyer, and driving means connected to one of the sprocket wheels for moving the conveyer, said rods and shafts being disposed in substantially longitudinal alignment so that the conveyer passes over the sprocket wheels without increasing the width of the openings between the rods and thus precludes the briquettes on the conveyer from falling therethrough.

5. A continuous sectional cooling conveyer for briquettes including a series of longitudinally disposed guard plates constituting the sides of the conveyer, each plate having a smooth inner sur-

face and provided at its inner side with a longitudinally extending enlarged offset portion, said offset portion being provided intermediate its ends with inwardly disposed spaced sockets and through openings, one of the offset portions terminating in a transversely disposed boss and the other end provided with a laterally offset boss arranged to overlap the boss on the adjacent plate when the parts of the conveyer are set up, the overlapped bosses having registering openings, grid rods extending transversely of the conveyer and having their ends mounted in aligned sockets in each opposed pair of plates, tie rods extending transversely through aligned openings in each opposed pair of plates, means for rigidly securing the tie rods to the plates, shafts extending through the openings in the aligned bosses for connecting the adjacent ends of the plates together, said shafts having rollers thereon for supporting the conveyer, said rods and shafts 20 constituting a slatted bottom for the conveyer and being correctly spaced to support the briquettes so as to prevent the latter from falling falling through the bottom and also being disposed to provide a maximum amount of open 25 spaces in the bottom effectively to cool the briquettes carried on the conveyer, and longitudinally disposed means connected to the shafts and the rods between each pair of opposed plates for rigidifying the conveyer.

GUSTAV KOMAREK.
